US00D787326S

(12) **United States Design Patent** (10) Patent No.: **US D787,326 S**
Hanson et al. (45) Date of Patent: **** May 23, 2017**

(54) **CAP WITH ACTUATOR**(71) Applicant: **Homax Products, Inc.**, Bellingham, WA (US)(72) Inventors: **Randal W. Hanson**, Bellingham, WA (US); **Robert A. Kinzle**, Polson, MT (US)(73) Assignee: **PPG Architectural Finishes, Inc.**, Pittsburgh, PA (US)(**) Term: **14 Years**(21) Appl. No.: **29/511,295**(22) Filed: **Dec. 9, 2014**(51) LOC (10) Cl. **09-07**

(52) U.S. Cl.

CLAIM

The new design for a cap with actuator, as shown and described herein.

DESCRIPTION

FIG. 1 is a front elevation view of a cap with actuator showing our new design;

FIG. 2 is a first side elevation view thereof;

FIG. 3 is a second side elevation view thereof;

FIG. 4 is a rear end elevation view thereof;

FIG. 5 is a top plan view thereof; and,

FIG. 6 is a bottom plan view thereof.

The evenly broken lines are shown for the purpose of illustrations of parts of the article that form no part of the claim. The dot-dash broken lines are shown for the purpose of illustrating environmental structure and form no part of the claim.

1 Claim, 3 Drawing Sheets
